UNITED STATES PATENT OFFICE.

FRED A. THOMPSON, OF NEWARK, NEW JERSEY.

DESIGN FOR AN ADVERTISING DISPLAY FORM.

Application filed August 11, 1927. Serial No. 23,059. Term of patent 7 years.

To all whom it may concern:

Be it known that I, FRED A. THOMPSON, a citizen of the United States, residing in Newark, in the county of Essex and State of New Jersey, have invented a new, original, and ornamental Design for an Advertising Display Form, of which the following is a specification, reference being had to the accompanying drawing, forming a part thereof.

Fig. 1 is a front view of the advertising display form showing my new design.

Fig. 2 is a side view thereof.

I claim:

The ornamental design for an advertising display form as shown.

F. A. THOMPSON.
